Primary Examiner — Rhea Shields(74) *Attorney, Agent, or Firm* — Dale J. Ream**CLAIM**

The ornamental design for a cardiopulmonary resuscitation pillow, as shown and described.

DESCRIPTION

FIG. 1 is a perspective view of a cardiopulmonary resuscitation pillow showing my new design;

FIG. 2 is a perspective view thereof;

FIG. 3 is a bottom view thereof;

FIG. 4 is a top view thereof;

FIG. 5 is a left side view thereof;

FIG. 6 is a right side view thereof;

FIG. 7 is a front view thereof; and,

FIG. 8 is a back view thereof.

In FIG. 1, the broken lines are for the purpose of illustrating environment only and form no part of the claimed design.

1 Claim, 4 Drawing Sheets(56)
